UNITED STATES PATENT OFFICE.

LEONARD L. DAVIS, OF SPRINGFIELD, MASSACHUSETTS.

SPIRIT-LEVEL.

SPECIFICATION forming part of Letters Patent No. 268,634, dated December 5, 1882.

Application filed May 12, 1881. (No model.)

To all whom it may concern:

Be it known that I, LEONARD L. DAVIS, a citizen of the United States, residing at Springfield, Hampden county, State of Massachusetts, have invented a new and useful Improvement in Spirit-Levels, of which the following is a specification.

In the drawings, Figure I is a side elevation of that portion of a spirit-level to which my invention is applied, with part of the graduated ring broken away to show the details of the adjusting arrangement, and in partial section. Fig. II is a plan view of same portion of said spirit-level, and Fig. III is an enlarged detail view of one of the adjusting-screws.

This invention relates to improvements upon the invention for which patent was granted me March 17, 1868, No. 75,533, in which a revolving bubble-case is embedded in the frame of a level to have the bubble-glass adjustable with reference to the outer frame or base of the level by means of screws provided with conical points and arranged to project inward and move against studs upon the bubble-case, having corresponding beveled ends, and their longer axes coincident to that of the screws to, by the movement of said screws, adjust the bubble-glass in reciprocating it; and this invention consists more particularly in an improved construction and arrangement of the adjusting mechanism to the bubble-glass.

In the drawings, *a* represents the socket or receptacle into which is inserted and in which revolves or oscillates the ring *D*, having therein the bubble case *C*. The ring *a* is perforated on each side, said perforations having screw-threads cut therein, and extending to and from one of the longer bearing-surfaces of the level at a right angle thereto, and so as to consequently cut the inner surface of the ring at a tangent, and the screws *d d'* are turned into the said threaded perforations, their ends *e e'* protruding beyond the inner surface of the ring *a* and into the space between it and the ring *D*, exactly opposite each other. Into the ring *D* are placed the studs *i i'*, which may be secured in place by any convenient and proper method, and so placed that when the ring *D* is in place in its socket *a* the studs *i i'* shall be in the same vertical plane with the screws *d d'*. The stud *i* is set into the ring *D* at a distance from the stud *i'*

equal to one-fourth of the whole circumference of the ring *D*, and they are so arranged that when the bubble-case *C* or ring *D* be turned one-quarter of a revolution the stud *i* impinges against the end of screw *d*, as shown in dotted lines.

I prefer to have the ends of screws *d d'* cut square off, and the studs *i i'* against which they come in contact of cylindrical form, though a departure from this configuration in either would be immaterial.

The operation of my invention is as follows: If it is found upon trial that the bubble-glass is not in perfect adjustment with the base of the frame *B'*, and it should be necessary to depress the side *E* of the bubble-case *C*, the screw *d'* is turned in; and its end *e'*, in its contact with the stud *i'*, forces it downward, which action elevates the other side, *F*, of the bubble-case *C*, and the screw may be correspondingly turned out, if desirable.

It will be seen that by this construction and arrangement of the parts of the adjusting mechanism a greater latitude of adjustment is possible, and that the wear of the impacting-surfaces of studs and screw ends can to any extent be taken up by the movement of the screw, whereas in the patented device before cited the extent of oscillation given to the bubble-case was limited to the distance the screws could move before having their ends bring up against the ring *D*, and any wear of the bearing-surface of the studs served to shorten that distance. The position of the heads of the adjusting-screws in this device possesses also great advantage over that occupied by the corresponding parts as formerly arranged, inasmuch as now the screw-driver for moving them can be held in a position to avoid injuring the screws, and so that their movement by hand can be more accurately regulated.

What I claim is—

In combination with the studs *i i'* upon the rotary reciprocating ring *D*, the adjusting-screws *d d'*, arranged in the frame tangentially to the bubble-case, to operate substantially as shown and described.

L. L. DAVIS.
